METALLIC CLOSURE

Arnold R. McCombs, Lancaster Township,
Lancaster County, Pa., assignor to Armstrong
Cork Company, Lancaster, Pa., a corporation of
Pennsylvania

Application June 30, 1934, Serial No. 733,195

12 Claims. (Cl. 215—43)

My invention relates to metallic closures and more particularly to the so-called "double shell" closures commonly used in sealing bottles and jars. These double shell closures are generally formed of an inner cap, which is provided with means for removably securing the cap to a receptacle, and an outer shell telescoped over the inner cap and covering the skirt and at least a portion of the top thereof. The outer shell is usually smooth surfaced throughout for appearance and in order to permit decoration of the top and skirt. The shell may, however, be embossed or otherwise formed as desired. The cap and shell are formed of light-weight sheet metal, such as tin plate, which is readily drawn and shaped to the desired contour.

One of the major problems incident to the manufacture of a closure of this type is to prevent relative rotation of the cap with respect to the outer shell. The closures are usually so constructed that they are inseparable without mutilation and upon sticking of the component engaging means, such as screw threads, caused by the application of the closure to the receptacle with great turning effort or by reason of adhesion, the turning effort required to overcome such friction or adhesion is greater than that required to cause the locking means to fail, whereupon, the outer shell rotates while the cap remains immovable. The cap is then removable only by mutilation of the outer shell. As an example, a 28 millimeter screw closure having well formed threads and applied to a properly finished glass container in the usual manner will require an average of 13.4 pound inches turning effort for removal, whereas, the same closure when applied tightly or adhesively secured by reason of corrosion or seepage of the contents of the receptacle, may require as much as 30 pound inches turning effort for removal. It will be apparent, therefore, that the interlocking of the cap and shell must be such that relative rotation of the parts will not occur by reason of the excess stress required to remove a tight fitting closure.

Various types of locking constructions have been suggested, many of which are commercially impracticable and others, while they can be produced and are effective for preventing such relative rotation, require intricate machinery for manufacture and assembly and are relatively expensive to produce.

It is an object of my invention to provide an improved type of closure in which relative rotation of the inner cap with respect to the outer

shell is effectively prevented even under abnormal conditions. It is a further object of my invention to provide a method of forming closures which is capable of being carried out on relatively simple assembly and drawing machines; which does not require commercially impracticable tolerances in the size of the component parts and which permits rapid formation and assembly.

My invention contemplates a closure in which the receptacle engaging portion is held in fixed position with respect to the outer shell by means of a flange provided on the skirt of the inner portion terminating in a cut surface, which when urged into engagement with the skirt of the outer shell, causes frictional or cutting engagement, preventing relative rotation of the parts. In the preferred embodiment, an outwardly and downwardly extending flange is provided on the skirt of the inner cap, which flange is urged upwardly and outwardly into firm engagement with the skirt of the outer shell. Stated in other words, the outwardly and downwardly extending flange is capable of being flexed whereby the diameter thereof may be decreased to permit ready assembly of the cap and shell and increased to cause locking engagement of the component parts.

The method consists in urging an outwardly extending flange terminating in a cut surface into engagement with the inner surface of the skirt of an outer shell telescoped over an inner cap, upon the skirt of which said flange is formed, by changing the diameter of at least one of the parts whereby the cut surface firmly engages the skirt of the outer shell and prevents relative rotation between the cap and shell. The method further contemplates urging an outwardly and downwardly extending flange upwardly and outwardly into engagement with the inner surface of the skirt of the outer shell.

In order that my invention may be more clearly understood, I will describe the same in connection with the attached drawing in which—

Figure 1 is an exploded view partly in elevation and partly in section showing an outer shell and an inner cap prior to assembly;

Figure 2 is a view partly in elevation and partly in section showing the preferred embodiment of my new closure;

Figure 3 is a view partly in elevation and partly in section showing a modified construction;

Figure 4 is an enlarged section taken on the line IV—IV of Figure 3;

Figure 5 is a diagrammatic view illustrating the

relative position of the flange with respect to the outer shell; and

Figures 6, 7, 8 and 9 are broken sectional views showing modified embodiments of my invention.

5 Referring first to Figure 1, an outer shell 2 is formed from a blank of sheet metal, such for example as 32 gauge tin plate which may be first suitably decorated as by lithographing. This shell is provided with a top portion 3 and a depending skirt portion 4 which is formed by a single, simple drawing operation familiar to those skilled in the art.

An inner cap, generally indicated by the numeral 5, is formed from a blank of tin plate in 15 two operations; a shell similar to the shell 2, but having the exposed edges of the skirt formed into a flange, being first drawn and this shell thereafter passing into engagement with a screw threading and knurling die whereby a thread 6 20 and a knurled portion 7 are formed on the skirt. As shown in the drawing, the top 8 may be flat, or if desired, may be contoured to provide a liner forcing annulus and have a dome shaped top as 25 shown in Figure 6. In the event the top 8 be domed, as shown in Figure 6, it is desirable to have the top 3 of the outer shell also domed, with the radius of curvature of both the same, so that the outer shell will not be deformed upon subsequent assembly of the two parts. Screw threads 30 have been illustrated as providing means for removably securing the closure to a receptacle. Other types of engaging means may be substituted for these screw thread formations.

According to my preferred embodiment, a 35 flange 9 is provided upon the exposed edge of the skirt of the inner shell terminating in a cut surface. As pointed out above, this flange may be formed during the original drawing operation and if so formed it will have a tendency to be irregularly shaped, or, in other words, will vary in 40 length from the line of intersection with the skirt to the edge thereof. It is desirable to trim this flange to a uniform and desired size and this may be conveniently done by means of a horizontal 45 punch type cutting machine.

In Figure 1, the flange extends at an angle of about 105° with respect to the skirt of the cap. This angle permits ready assembly and subsequent deformation. The particular angle to be 50 employed is not critical although the flange should, in order to provide the preferred biasing action, extend outwardly and downwardly. As is better illustrated in Figure 5, the flange length from the line of intersection 10 with the skirt 55 to the exposed edge 11 of the flange 9 is greater than the distance from any point on the line 10 to a corresponding point 12 on the inner surface of the skirt of the outer shell lying in a plane normal to the axis of the cap, or stated in other 60 words, an arc swung from any point on the line of intersection 10 having a radius equivalent to the skirt length will intersect the inner surface of the skirt of the outer shell. This is desirable in order that upon upward movement of the 65 flange 9 about the line of intersection 10, the flange will firmly engage the surface 13 before reaching a position normal to the axis of the cap. The difference in length between the flange 9 and the line 10—12 will depend to some extent upon 70 the deformability of the outer shell.

To insure that the cap be properly positioned with respect to the outer shell, I prefer to have the flange formed with an outer diameter slightly greater than the inner diameter of the shell. The 75 flange is sufficiently flexible to permit telescoping

of the two parts and the inner cap having a flange about .002" greater in diameter than the inner diameter of the outer shell is readily assembled by means of an inserting plunger. The cap and shell may be forced into position with the head portions 3 and 8 in engagement, or, if desired, a cardboard or other cushioning disk D may be inserted therebetween as shown in Figure 7.

After telescoping, the cut surface of the flange is urged into firm engagement with the inner 10 surface of the skirt of the shell. This may be accomplished by decreasing the inner diameter of the skirt of the shell or by increasing the diameter of the flange on the cap, or both. The diameter of the skirt may be reduced by curling the 15 exposed edge thereof under the flange whereby the skirt will curl inwardly from the line of contact with the flange, whereby the frictional grip of the metal parts, enhanced by the action of the cut surface, will prevent rotation. 20

I prefer, however, to urge the flange 9 upwardly whereby the outer diameter thereof is increased and the cut surface firmly engages the inner surface of the outer shell. Various means may be employed for urging the flange upwardly, such 25 for example as a suitably shaped plunger having an outer diameter substantially the same as the inner diameter of the outer shell. The cut surface has a tendency to be somewhat roughened as is common in cut metallic surfaces of this type 30 and this surface upon being forced upwardly against the metal of the outer shell forms microscopic grooves therein which greatly enhance the frictional grip. The flange which is normally biased downwardly and out of the position it now 35 assumes should preferably be held in strained or upward position, which, as shown in Figure 2, lies at an angle slightly greater than 90° with respect to the skirt of the cap. It is desirable, although not essential, that the entire cut surface 14 of 40 the flange engage the shell because of the increased frictional grip provided thereby. There may be a slight deformation of the outer shell by reason of the pressure applied by the flange if 45 32 gauge tin plate is used, but this will not be noticeable. The flange may be held in proper position by any simple deformation of the skirt of the outer shell below the line of contact with the flange. A plurality of indentations may be 50 employed or the exposed edge of the skirt may be turned under the flange thereby holding it in strained position. Any angularly extending portion provided on the outer shell which holds the flange in such position without materially weakening the frictional grip will be satisfactory. 55

If desired, the skirt of the outer shell may be deformed prior to insertion of the cap and the flange then urged into its strained position snapping under the deformed portion of the shell. According to my preferred embodiment, however, the flange is urged upwardly and the outer shell deformed by a single operation. As shown in Figure 2, this is accomplished by forming an inwardly, upwardly and outwardly extending bead 15 into engagement with the flange 9 whereby the flange is urged into firm engagement with the shell and held in that position by the bead. A simple crimping or curling tool of the type now employed in the metallic closure art may be used for this purpose. The bead 60 may be turned so that the cut edge thereof engages the inner surface of the shell. It is desirable that no cut surfaces be exposed which might have a tendency to become corroded upon contact with the contents of the bottle. A some- 65 70 75 75

what enhanced gripping action will be obtained, however, if the cut surface of the exposed edge of the outer shell engages the inner surface of the flange. This is accomplished by turning the bead inwardly and upwardly and if desired outwardly to an extent sufficient to insure that the cut surface of the skirt of the outer shell will properly engage the under side of the flange as shown in the drawing. The formation of the bead to accomplish this enhanced gripping action is dependent to some extent upon the angle assumed by the flange when forced into final position.

In Figures 3 and 4 a modified construction is illustrated in which the flange 16 has formed on the exposed edge thereof a plurality of serrations or tooth-like elements 17. These may be formed during the flange trimming operation by the use of a suitably shaped cutting die. I have found that if the portion between the cuts is about four times the width of the cut a desirable gripping action is obtained. This is probably due to the fact that, upon being urged upwardly, the tooth-like elements 17 have a tendency to scrape the metal, leaving the metal uncut in the portions 18 between the teeth. In other words, the skirt of the outer shell is provided with shallow indentations corresponding to the teeth 17 and raised portions 18 therebetween. This forms a highly desirable interlocking engagement of the parts which is enhanced by reason of the fact that the teeth 17 engage the surface of the skirt and also aid in preventing relative rotation. The formation or shape of the serrated edge is not controlling, although I have found that when serrations terminating in sharp points have been employed they have a tendency to become distorted upon the application of pressure and are not as effective as relatively flat surfaces with narrower slots cut therebetween.

While it is desirable that the flange terminate in a cut surface, it will be understood that the flange may be provided with a bead or turned in portion B as shown in Figure 8 which will present a smooth surface for engagement with the outer shell. This will eliminate the trimming operation referred to above but will necessitate another forming operation.

As is common in this art, the outer covering has been called a shell and the inner portion a cap. It will be understood that the shell need not cover the entire top portion, but if it be as shown in the drawing, Figures 1 to 5, the cap may be in the form of an annulus A as shown in Figure 9 having a shoulder S rather than a complete top with engaging means and a deformable flange. The preferred construction, however, is the form illustrated, wherein both shell and cap are provided with a complete top and skirt.

While I have described and illustrated the preferred embodiment of my invention, it will be understood that the invention is not so limited but may be otherwise embodied within the scope of the following claims.

I claim:

1. A double shell closure comprising an inner metallic cap and an outer metallic shell, an outwardly and downwardly directed expandible flange on the skirt of the cap engaging the inner surface of the shell and biased downwardly, and an angularly extending portion on the skirt of the shell engaged with the lower face of said flange and holding said flange in strained posi-

tion against the tendency to return to its normal position.

2. A double shell closure comprising an inner metallic cap and an outer metallic shell, an outwardly and downwardly directed expandible flange on the skirt of the cap engaging the inner surface of the shell and biased downwardly, and a bead formed on the exposed edge of the skirt of said shell holding said flange in firm engagement with said shell and in strained position. 10

3. A double shell closure comprising an inner metallic cap and an outer metallic shell, an outwardly and downwardly directed expandible flange on the skirt of the cap lying at an angle greater than 90° with respect to the skirt of said cap and terminating in a cut surface lying in firm engagement with and penetrating the material of the skirt of said shell, and an angularly extending portion on the skirt of said shell engaged with the lower face of said flange and holding said flange 20 in fixed position.

4. A double shell closure comprising an inner metallic cap and an outer metallic shell, an outwardly and downwardly directed expandible flange on the skirt of the cap having a serrated 25 surface lying in firm engagement with the skirt of the outer shell, said flange being biased downwardly and an angularly extending portion on the skirt of the shell below the line of contact of said flange holding said flange in strained 30 position.

5. A double shell closure comprising an inner metallic cap and an outer metallic shell, a flange on the skirt of the cap having a serrated surface in which the tooth-like elements are at least 35 four times the width of the cut portions, said tooth-like elements engaging the inner surface of the skirt of the outer shell, raised portions on the skirt of the outer shell intermediate the tooth-like elements and a bead on the skirt of 40 the outer shell in firm engagement with said flange.

6. A double shell closure comprising an inner metallic cap and an outer metallic shell, a flange on the skirt of the cap biased downwardly and 45 terminating in a cut, serrated surface, the serrated surface of the flange engaging the skirt of the outer shell, with raised portions intermediate adjacent serrations, and an angularly extending portion on the skirt of the outer shell 50 below the line of contact of the flange holding said flange in strained position.

7. A double shell closure comprising an inner cap having a top and a skirt, an outwardly directed expandible flange formed on said skirt biased downwardly, an outer shell telescoped over the cap, a bead formed on the exposed edge of the skirt of said shell terminating in a cut surface firmly engaging said flange and holding the same in strained position. 60

8. A double shell closure comprising an inner cap having a top and a depending skirt provided with means for removably securing said closure to a receptacle, an outwardly and downwardly directed expandible flange formed on said skirt 65 biased downwardly, said flange normally extending at an angle substantially greater than 90° with respect to the skirt, an outer shell having a top and a depending skirt, a bead formed on the end of said skirt engaging the flange on 70 the skirt of said cap and urging the same into firm engagement with the skirt of the outer shell at an angle of substantially 90° with respect to the skirt of said cap and holding the same in strained position. 75

9. A double shell closure comprising a screw threaded cap telescoped within an outer shell, an expansible flange on the skirt of the inner cap normally lying in a frusto-conical surface, a bead formed on the exposed edge of the skirt of the outer shell engaging said flange and holding the same in firm engagement with and penetrating the material of the skirt of the outer shell and in a geometric surface substantially approaching a plane normal to the axis of the cap against the tendency to lie in a frusto-conical surface.

10. A double shell closure comprising an inner metallic cap and an outer metallic shell, an outwardly directed and downwardly biased expansible flange on the skirt of the cap terminating in a cut surface lying in firm engagement with the skirt of the outer shell and a bead on the skirt of the outer shell terminating in a cut surface lying in firm engagement with said flange and holding the same in strained position.

11. A screw cap embodying therein a skirted outer shell, and an inner shell inclosed thereby having a skirt provided with means adapted to engage complementary means upon a container,

and with an outwardly directed expansible edge portion having its edge engaged with, and penetrating the material of the skirt of said outer shell, the lower edge of the skirt of said outer shell being turned inwardly and upwardly upon itself and engaged with the lower face of said outwardly directed expansible portion of said inner shell.

12. A screw cap embodying therein a skirted outer shell having the lower edge of the skirt turned inwardly of the shell, and an inner shell inclosed thereby having a skirt provided with means adapted to engage complementary means upon a container, and an outwardly and downwardly directed flange about the bottom thereof having a plurality of deformed edge tangs, said tangs penetrating the material of the skirt of the outer shell, and the inwardly turned edge of the skirt of the outer shell frictionally engaging said flange intermediate said tangs and the skirt of the inner shell, and said tangs being clamped between said turned portion and the skirt of the outer shell.

ARNOLD R. McCOMBS. 25
